UNITED STATES PATENT OFFICE.

CHARLES WILLIAM SCHLEIER, OF DETROIT, MICHIGAN.

ELEVATED LANDING PLACE FOR AEROPLANES.

Application filed June 14, 1921. Serial No. 477,488.

To all whom it may concern:

Be it known that I, CHARLES W. SCHLEIER, a citizen of the United States, residing at Detroit, in the county of Wayne and State 5 of Michigan, have invented new and useful Improvements in Elevated Landing Places for Aeroplanes, of which the following is a specification.

This invention relates to a landing for 10 aeroplanes or any other mode of aircraft to alight upon for parking purposes, the principal object of the invention being to provide a landing place up in the air to overcome the necessity of descending to the 15 ground for parking or repairs or loading and unloading passengers or freight, by means of an elevated platform supported by uprights with their bases on the ground or embedded in the ground, said elevated 20 platform landing provided with means for facilitating the loading or unloading of the airship or other aircraft.

Another object of the invention is to provide means for turning the airship upon the 25 platform so that it can be turned to face the direction of flight.

Another object of the invention is to provide hinge members with means for raising them to an inclined position to cause the 30 airship to take the air with its nose pointed upwardly as it leaves the landing, or to move said members into a vertical position to prevent the ship from being accidentally moved off the landing.

35 This invention also consists in certain other features of construction and in the combination and arrangement of the several parts, to be hereinafter fully described, illustrated in the accompanying drawings 40 and specifically pointed out in the appended claims.

In describing my invention in detail, reference will be had to the accompanying drawings wherein like characters denote 45 like or corresponding parts throughout the several views, and in which:

Figure 1 is a side view of the invention.

Figure 2 is a plan view.

Figure 3 is a transverse sectional view on 50 line 3—3 of Figure 2.

Figure 4 is a section on line 4—4 of Figure 2.

Figure 5 is a fragmentary detail view of the means for actuating a bridge.

55 In these views 1 indicates a platform

which is supported by the uprights 2, these uprights being of any desired height. A small platform 3 is arranged on the main platform 1, adjacent one side thereof, and a waiting room 4 may be located on the main platform with its entrance opening out upon the platform 3. Elevators 5 are provided for carrying passengers and freight to and from the landing and these elevators have their upper entrances opening out upon the platform 3. A stairway 6 is also provided and this stairway has its entrance opening out upon the platform 3. Swinging bridges 7 are hinged to the outer side of the platform 3 and are adapted to extend to the ship so as to permit the freight and passengers to be unloaded or loaded, said bridges being necessary on account of the fact that the ship cannot be brought close to the platform 3 on account of its wings. These bridges can be actuated by the drums 8 and the cables 9. A turn-table 10 is placed at the center of the main platform 1, this table consisting of a circular platform 10' having rollers 11 upon its under face which engage a flange 12 extending inwardly from the walls of the circular opening 13 formed in the landing. A post 14 supported upon the framework 15 has its upper end in alignment with the center of the turn-table and a tubular member 16, connected with the center of the table, engages said post. Thus the table is rotatably supported within the opening and it may be provided with loops 17 by which it may be rotated.

Recesses 18 are formed in the ends of the landing or platform 1, flanges 19 being formed upon the side walls of each recess and plates or members 20 have their inner edges hinged to the end walls of said recesses. These plates engage the flanges 19 when in lowered position so as to cover the recesses and in this position the upper faces of the members are flush with the surface of the platform. Handles 21 are attached to said members and a curved rack 22 is connected with the bottom of each member and this rack engages a pinion 23, mounted on the crank shaft 24, so that it can be rotated either by hand or by power to raise or lower the member 20. Each member 20 carries a pair of latch members 25 which are adapted to engage holes 26 in the handles 21 so as to hold said members 20 in vertical position.

tion. Such members can be held in inclined position by the gears and racks when desired.

A guard rail 27 is placed around the platform 1 and a gutter 28 is placed around the supporting structure below the level of the platform 1 for catching objects dropping off the platform.

It will thus be seen that an airship can easily land on the structure and have its cargo and passengers discharged over the bridges 7 onto the platform 3. The passengers and freight are then lowered to the ground by the elevators. The ship can be loaded in the same way.

The turn table will permit the ship to be headed in the direction of flight and the members 20 can be raised to an inclined position so that the ship when passing over the same will have its nose raised as it takes the air so as to facilitate its elevation. If the ship is to remain on the landing the members 20 can be raised to vertical position with the ship between them so as to prevent the ship from being accidentally moved off the platform.

By making my structure of a suitable height platform 1 can be placed above surrounding buildings so that the airship or other aircraft can land in a city or town.

The drawings show a building 4' upon the main platform which contains the waiting room 4, the upper ends of the elevators and the stairway and the building 4" upon the ground containing the entrances for the elevators and stairway.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A landing for airships comprising a platform, a supporting structure for the same, a hinged member at one end of the platform normally forming a part of the platform, means for tilting the member to cause the nose of the ship to be elevated when taking the air and means for holding

said member in vertical position to act as a guard for the ship.

2. A landing for airships comprising a platform, a supporting structure for the same, elevators for carrying passengers and freight to the platform, a small platform on the main platform arranged adjacent the upper ends of the elevators and draw bridges connected with the small platform.

3. A landing for airships comprising a main platform, a supporting structure for same, a hinged member at one end of the platform normally forming a part of the platform, a small platform arranged on the main platform, swinging portions hinged to the outer side of the small platform and being adapted to extend to a ship, drums and cables actuating said portions, means for tilting the hinged member to cause the nose of the ship to be elevated when taking the air and means for holding said member in vertical position to act as a guard for the ship, a guard rail being placed around the platform and a gutter placed around the supporting structure below the level of the platform for catching objects dropping therefrom.

4. A landing for air ships comprising a platform, uprights supporting said platform, a small platform arranged on the main platform adjacent one side thereof and a waiting room located on said main platform having its entrance opening upon the small platform, means for transporting passengers and freight to and from the landing, a turn table upon the platform for turning the ship and means upon the platform for facilitating the loading and unloading of the ship, said table being rotatably supported and being provided with loops by which it may be loaded, said main platform having recesses formed in its ends and flanges formed upon the side walls of the recess, plates having their inner ends hinged to the end walls of said recess, means for turning the member to cause the nose of the ship to be elevated when taking the air and means for holding said member in vertical position to act as a guard for the ship.

In testimony whereof I affix my signature.

CHARLES WILLIAM SCHLEIER.
